UNITED STATES PATENT OFFICE.

DE WITT H. WYATT AND WILLIAM C. GROENIGER, OF COLUMBUS, OHIO, ASSIGNORS TO THE GROENIGER MANUFACTURING COMPANY, OF COLUMBUS, OHIO, A CORPORATION OF OHIO.

OUTLET CONNECTION FOR PLUMBING FIXTURES.

Application filed June 23, 1920. Serial No. 391,146.

To all whom it may concern:

Be it known that DE WITT H. WYATT and WILLIAM C. GROENIGER, citizens of the United States, residing at Columbus, in the county of Franklin and State of Ohio, have invented certain new and useful Improvements in Outlet Connections for Plumbing Fixtures, of which the following is a specification.

This invention relates to an improved outlet connection for water closets, and has for its object to provide a connection of this character wherein an improved joint structure is provided between the outlet portion of a closet and the co-operative waste pipe structure thereof, the construction being such as to permit of the convenient assembling of the various parts comprising the connection, to permit of the use of standardized parts, and to enable the connection to adapt itself to such irregularities that may exist even when standard parts are employed. Other objects will be in part obvious and in part pointed out hereinafter. The invention accordingly consists in the novel features of construction, combinations of elements and arrangement of parts, hereinafter to be fully described and to have the scope thereof pointed out in the appended claims.

In the accompanying drawings, forming a part of this specification, and in which similar characters of reference denote like and corresponding parts:

Figure 1 is a vertical sectional view taken through the improved closet connection comprising one of the preferred forms of the invention, the connection being such as is employed with cast iron waste or soil pipes,

Figure 2 is a similar sectional view disclosing the form of the connection when employed in conjunction with a slightly modified form of seating cup,

Figure 3 is a vertical sectional view showing the form of the connection when employed in connection with a lead soil pipe,

Figure 4 is a similar view disclosing more particularly the form of the connection when the latter is employed in co-operation with a wrought iron soil pipe,

Figure 5 is a top plan view showing a form of test plug capable of obstructing the connection when the latter is employed under test conditions,

Figure 6 is a detail sectional view taken through the test plug on the line 6-6 of Figure 5, and

Figure 7 is a sectional view showing a slightly modified form of gasket construction.

Referring to the drawings and more particularly to the embodiment of the invention disclosed in Figure 1, the water closet typical of a bath room fixture is indicated by the numeral 1; the latter may be of any desired construction and adapted for any use whatsoever so far as this invention is concerned. The outlet for said closet is indicated by the numeral 2, and in the form illustrated said outlet is of substantially tubular formation, and its lower edge 3 is disposed to terminate substantially on the same horizontal plane as the upper surface of the floor or base 4 upon which the closet 1 is mounted. Preferably, the outlet 2 is provided, contiguous to its lower end, with an integral collar 5, which is concentrically positioned with respect to the outlet 2 and is of such form as to surround and enhouse the connection opening 6 formed in the floor or base 4. The outer edge of the collar 5 is provided with a depending rib 7, which engages with the upper surface of the floor, and it will be observed, therefore, that the resting surface of the rib 7 is on the same horizontal plane as the lower edge 3 of the closet outlet. An annular space 8 is provided, by means of this construction, between the lower wall of the outlet 2 and the rib 7, and it is to this space that the seating connection for the closet is positioned.

The seating structure, in the form illustrated in Figure 1, consists of a sleeve 9, which is positioned within the base opening 6 and is concentrically disposed with respect to the outlet end of the closet. In this instance the sleeve 9 is provided with a plurality of integral laterally projecting, slotted ears 10, which are disposed to engage with the upper surface of the floor 4 and are enhouised by the collar 5. Through the provision of the ears 10 it will be manifest that a support is provided for the sleeve 9 and one fully capable of withstanding such stresses as may be imparted thereto. Head bolts 11 are positioned within the slots of the ears 10, and the shanks of the bolts extend upwardly through elongated slots 12.

provided in the collar 5. Nuts or their equivalents 13 are carried by the upper ends of the bolts and are arranged to frictionally press upon suitable washers 14, in order that the operative position of the outlet 2 may be maintained with respect to the sleeve 9, and to thereby maintain the relative concentricity between parts. It is also obvious that through the agency of the bolts 11, a secondary support will be provided for the sleeve.

In the form of the invention under discussion, the sleeve 9 has its upper end internally threaded as at 15 for the reception of a metallic seating cup 16. This cup is provided with a head portion 17 normally disposed within the space 8, and the periphery of the portion 17 terminates in a flange 18, which is seated upon the upper end of the sleeve 9. Further, the head portion is provided with an upstanding substantially annular rib 20, which concentrically surrounds the mouth of the outlet 2. This rib also serves to maintain the relative positions of the seating cup with respect to the closet outlet and consists in sealing the connection against the escape of liquid or obnoxious gases. The head portion terminates in a downwardly extending ring 21, which in effect forms a continuation of the outlet 2 and is so positioned as to be concentrically spaced from the sleeve 9. As shown, the ring 21 is provided with an annular flange in the form of a seat 22, which is so positioned as to receive the annular surface formed upon the extreme lower edge 3 of the outlet, and a sliding gasket 23 is preferably carried by the seat and is so arranged as to directly receive the edge 3 and to thereby seal the joint between the outlet 2 and the waste pipe connections. The seat or flange 22 is so positioned and proportioned that when the closet 1 is operatively positioned the outlet end thereof will be directly deposited upon the gasket 23. The parts are so proportioned that this fit will obtain without any adjustment on the part of the fitter, and hence a sealed joint is produced which will effectively prevent escape of fluids passing through the connection. This seating of the outlet 2 may be secured by so proportioning the parts that the edge 3 will be situated on the same plane as the resting edge of the collar 5, or in other words on a plane corresponding to the upper surface of the base 4.

The slot or waste pipe 24 is of cast iron construction, and is arranged to be positioned between the flange 18 of the seating cup 16 and the inner wall of the sleeve 9, the upper edge of the pipe 24 terminating appreciably above the lower portion of the ring 21, and in spaced relationship from the inner wall of the sleeve 9. Hence, by the provision of the depending ring 21 the inaccuracies due

to floor warp or falling will be eliminated, since the space 25 is provided between the ring 21 and the sleeve 9 for this purpose. In other words, if the flooring should fall from a normal position, the upper end of the pipe 24 will merely project a greater distance into the space 25, and conversely, a slight degree of lifting from the normal on the part of the floor will be compensated for by the elongated ring 21, which is of sufficient length to always extend appreciably within the interior of the upper end of the pipe 24. This element of adjustability on the part of the connection is of considerable assistance in enabling the fitter to quickly and accurately assemble the joint construction without relying upon fine adjustments or close connections, and yet the construction is such as to block the undue escape of liquids or gases. To seal the joint between the upper end of the pipe 24 and the sleeve 9, the lower end of the latter is inwardly bent as at 26 to provide a seat for the reception of a fibrous calking material, which is firmly pointed into said space in a manner common to calking operations. The joint may be finally sealed by introducing a lead metallic packing 28 into said space so as to effect the final sealing of the joint. By virtue of this construction it will be manifest that an uninterrupted passageway will be provided for the flow of liquid through the outlet connection, and that all projections in the path of liquid flow are avoided. By the provision of the outlet construction described, and the seat 22 a firm union is provided between the lower end of the closet and the seating cup, and one through which gas or other fluid will be prevented from escaping.

Moreover, the outlet connection through the structure is not provided with any projections or crevices through which liquid or gas may have a tendency to seat and find outlet; all of the joints are firmly sealed and are of such construction that relative play between parts will not result in the opening of the joints. Another desirable feature is the construction of the ring 21, which is so formed as to extend within the upper end of the waste pipe 24, whereby the connection as a whole may have relative movement with respect to said pipe without impairing the joint structure.

The form of the invention disclosed in Figure 2 is substantially the same as that set forth in Figure 1, with the exception that the modified form is particularly adapted for waste pipes of smaller diameter than that shown in Figure 1. This reduction in size allows of a slight change in the specific construction of the seating cup 16, which in the modified form is threaded in the usual manner into the sleeve 9 and provides the usual seat for the reception of the lower end of the outlet. In this latter form the rib 20

is omitted owing to the fact that the diameter of the head of the seating cup has been reduced to such extent as to permit its annular wall 29 to act in the same capacity as the rib 20. This change also results in causing the ring 21 of the seating cup to project into the space at the lower end of the outlet 2 to a greater extent than in the preferred form. Obviously, the form disclosed in Figure 2 is but slightly different from that set forth in Figure 1, and inasmuch as the same principles of operation and construction are present, it is believed that the form shown in Figure 2 is well within the scope of the invention. In Figure 3, the waste or soil pipe is formed from lead, instead of cast iron, as in Figures 1 and 2. The use of this material has of necessity resulted in a slight change in the construction of the sleeve 9, in order that a firm union between parts may be effected. The closet and seating cup construction disclosed in Figure 3 is exactly similar to that set forth in Figure 1, but in Figure 3 the sleeve 9 is terminated in an inwardly bent flange 30, which is so projected as to lie immediately beneath the head of the seating cup. This flange 30 is sufficiently spaced from the outer walls of the seating cup so as to permit of the introduction of the upper end of the lead waste pipe 31 therebetween. The end of the pipe is then bent downwardly upon the flange 30, in order that the desired connection between the pipe 31 and the sleeve 9 may be effected. Since lead is the material from which the pipe 31 is formed, it is obvious that the adjustment found in Figure 1 between the waste pipe and the seating cup is not necessary, since the upper end of the pipe may be cut off or bent to compensate for irregularities in dimensions.

In Figure 4 the waste pipe 32 is formed from wrought iron, and has its upper end threaded as at 33. In this form of the invention the sleeves and seating cups, provided in the other forms of the invention, have been combined into one member, which will be termed for convenience of description, the seating member, and which is designated by the numeral 34. This member is supported by the usual ear extensions 35 and is threaded to the end 33 of the pipe 32. The threaded construction allows for adjustment between the upper end of the pipe 32 and the upper surface of the base 4. The interior of the member 34 is provided with an inwardly projecting flange 36, which constitutes a seat for the lower end of the closet outlet 2. Otherwise the construction disclosed in Figure 4 is the equivalent to that previously discussed.

Frequently it is desirable that the connections, or the water system with which they are inserted, be tested before the installation of the closets 1, in order that the leak-

age of the joints, if any, may be detected. Therefore, as shown in Figures 5 and 6, use is made of a test plug 37 which is so constructed as to be seated upon the seats found in the seating cups. These plugs are provided with lateral extensions 38, which are adapted to overlie the ears 10, in order that the plugs may be firmly secured in conduit closing relationship with respect to the cups or seating members by means of the bolts 11, or their equivalents. When the plugs are firmly positioned, it is obvious that fluid pressure may be introduced into the system in any suitable manner. If a leaky joint is then present, the fact will be made known by the escape of the fluid. In Figure 7 there is shown a sleeve centering gasket 39, which is employed in lieu of the gasket 23. In cross-section this gasket 39 is of angular formation, and is not only capable of engaging with the lower edge 3 of the closet outlet, but is also extended so as to surround the outer walls of the outlet. In other words, the gasket 39 is of such construction as to give the lower end of the outlet 2 into proper engagement with the seat 22 and to otherwise serve in preventing undue escape of fluid from the connection.

From the foregoing description, taken in connection with the accompanying drawings, it will be apparent that the present invention provides a form of outlet connection for closets and other plumbing fixtures wherein security is to be had in the assembling of the parts in such manner as to prevent fluid leakage, and further the construction is such as to allow for slight imperfections in the assembling of the various parts. The joint is particularly of standardized construction, and may be adapted to present types of plumbing fixtures. In this connection waste pipes of any standard material and size may be utilized, and a secure union may be had between the same and the seating members. Particularly, a joint connection is provided for accommodating the closets wherein the outlet portions thereof terminate flushly with a base surface.

What is claimed is:

1. An outlet connection for closet bowls, comprising a bowl wherein is embodied an outlet portion which is terminated to lie evenly with the supporting base upon which the bowl is mounted, a collar projecting from said outlet portion and formed to have its lower surface terminated on the same plane as the lower end of the outlet portion, a seating structure for said outlet connection, including a metallic ring concentrically disposed with respect to the major axis of the outlet portion and positioned beneath the latter, a supporting head for said ring situated within said collar and disposed for seating co-operation upon the sup-

porting base, a seat formed internally of said ring for the reception of the lower end of the outlet portion, means whereby a connection is established between the supporting head and collar, and an outlet pipe leading from said ring.

2. An outlet connection for water closets, comprising a sleeve arranged to be carried by a supporting base, a waste pipe joined to said sleeve interiorly thereof, a seating member separably carried by said sleeve and arranged to adjustably project into the upper end of said waste pipe, a seat formed upon said seating member and arranged to receive the lower end of the outlet portion of a water closet, said outlet portion terminating evenly with the supporting base.

3. In a connection of the class described, the combination with a closet having an outlet portion, a base upon which said closet is mounted, of a seating structure comprising a sleeve arranged to project through said base and in concentric relationship with said outlet portion, means carried by said sleeve for enabling the same to be supported by said base, a seating ring positioned within said sleeve and arranged for seating co-operation with the lower end of said outlet portion, and a waste pipe adjustably positioned between said seating member and the inner wall of said sleeve.

4. In an outlet connection for water closets, comprising a floor collar arranged to be positioned within an opening provided in a floor, lateral offsets formed on the upper end of said collar and engaging with the floor surface for supporting said collar over said surface when the collar is in its applied position, a seating ring adjustably connected with and supported by said collar, said ring being situated internally of said collar and provided with an offset flange constituting a seat for the outlet end of a closet bowl, and skirt depending from said ring and arranged to be received within the upper end of an outlet pipe.

5. In an outlet connection for water closets, an outlet horn having a lower packing engaging edge, a waste pipe adapted to receive the flow from said horn, a seating means detachably and slidably cooperating with the exterior of the upper end of said pipe, a seat projecting inwardly from said

means and underlying the edge of said outlet horn, and a packing carried by said seat.

6. In an outlet connection for water closets, an outlet horn having a lower packing engaging edge, a waste pipe adapted to receive the flow from said horn, a seating means cooperating with the exterior of the upper end of said pipe, a seat projecting inwardly from said means and underlying the edge of said outlet horn, and a packing carried by said seat.

7. In an outlet connection for water closets, an outlet horn having a substantially uniform flow opening therethrough and having a lower packing engaging edge terminating substantially even with the floor surface above which the closet is mounted, seating means for said edge having a supporting surface terminating substantially even with said lower packing engaging edge, and a packing carried by said seating means and adapted to be compressed vertically between said means and said edge.

8. In an outlet connection for water closets, an outlet horn having a substantially uniform flow opening therethrough and having a lower packing engaging edge, seating means for said edge having a supporting surface terminating substantially even with said lower packing engaging edge, said seating means having an inwardly projecting seat adapted to underlie said edge and providing a flow opening substantially equal to the flow opening through said horn, and a packing carried by said seat and adapted to be compressed vertically between said seat and said edge.

9. In an outlet connection for water closets, a waste pipe, a seating means detachably secured to the upper end thereof and carrying a packing, a closure adapted to cooperate with said packing for testing the connection, said packing being adapted to cooperate with the outlet horn of the closet when the connection has been tested and the closure removed, and means on said seating means and said closure for clamping the same together for testing purposes, said last mentioned means on said seating means being effective for supporting the same when in use.

In testimony whereof we affix our signatures.

DE WITT H. WYATT.
WILLIAM C. GROENIGER.

Certificate of Correction.

It is hereby certified that in Letters Patent No. 1,505,683, granted August 19, 1924, upon the application of De Witt H. Wyatt and William C. Groeniger, of Columbus, Ohio, for an improvement in "Outlet Connections for Plumbing Fixtures," an error appears in the printed specification requiring correction as follows: Page 4, line 82, claim 8, after the word "edge" and before the comma insert the words *terminating substantially even with the floor surface above which the closet is mounted*; and that the said Letters Patent should be read with this correction therein that the same may conform to the record of the case in the Patent Office.

Signed and sealed this 23d day of June, A. D. 1925.

[SEAL.]

KARL FENNING,
Acting Commissioner of Patents.
